UNITED STATES PATENT OFFICE.

WILLIAM H. DARRAH, OF BETHLEHEM, PENNSYLVANIA.

HOISTING DEVICE.

Application filed March 4, 1919. Serial No. 280,588.

To all whom it may concern:

Be it known that I, WILLIAM H. DARRAH, a citizen of the United States, residing at Bethlehem, in the county of Northampton 5 and State of Pennsylvania, have invented certain new and useful Improvements in Hoisting Devices, of which the following is a specification.

This invention relates to improvements in 10 hoisting devices, whereby handling of heavy materials is facilitated, and the principal object of the invention is to increase the efficiency of devices of this character by providing a novel arrangement of increased 15 power gearing between the lift and operating elements; by providing a novel form of automatic clutch mechanism to prevent accidental downward movement of the load from a hoisted position, but which will permit of free operation of the device to hoist 20 the load, by providing novel means to prevent tangling of the lift and operating elements, and by constructing the device simply from a minimum of parts, which are cheap 25 to manufacture.

With the foregoing and other objects in view, the invention consists in the novel features of construction, combination and arrangement of parts as will be hereinafter 30 more clearly described, illustrated in the accompanying drawings and claimed.

In the drawings,

Fig. 1 is a side elevation of the hoisting device constructed in accordance with the 35 invention parts being broken away,

Figure 2 is a cross-sectional view of the device, disclosing the arrangement of gearing, the section being taken in the vertical plane.

Fig. 3 is a fragmentary side elevation of 40 the device, parts being broken away,

Fig. 4 is a detail vertical section of the clutch elements, showing the same separated.

Fig. 5 is an inner face view of one of the clutch elements.

Referring to the drawings by numerals 45 wherein is illustrated the preferred embodiment of my invention, 1 designates what will be termed the gear frame and 2 designates what will be termed the clutch frame, these frames adapted to be connected to provide a single supporting frame for the operating mechanism to be hereinafter described.

The frame 1 is preferably circular in 55 shape, as is the frame 2, and these frames are

held in spaced relation by means of sleeves 3 through which pass bolts 4, the said bolts being also passed through lugs in the clutch frame and having threaded connections with the gear frame whereby the frames are held in rigid spaced relation.

Offset lugs 5 are formed upon the frames 1 and 2, and these lugs are adapted to be arranged in alignment to receive studs 6 carried by a block 7 whereby the same is pivotally mounted between the frames. This member 7 is provided with a central opening to receive the reduced end of a hook 8, the reduced end being extended through the member 7 and having a nut 9 threaded thereon to secure the hook to the frame. By this arrangement it will be noted that the hook 8 may be engaged with any suitable support and the frame will be permitted of 75 pivotal movement relative thereto.

Aligned openings are formed centrally in the frame members 1 and 2 to receive offset portions 9' upon either side of a wheel 10, anti-friction bearings in the nature of rollers 11 being arranged between the offset portions of the wheel and the walls of the openings to mount the wheel for free rotation between the frame members. This wheel 10 is provided upon its peripheral edge with 80 suitably formed depressions to receive the links of a lift element in the nature of a chain 12. The wheel 10 is arranged between the frame members 1 and 2, as is shown, and the offset portions 9' thereof extend past the outer faces of the frame members 1 and 2 any suitable distance, for a purpose which will presently appear.

Mounted upon the offset portion 9', extending past the outer face of the gear frame, 95 is a pinion 13 which is secured against rotation relatively to the wheel 10 by means of a key 14. This pinion 13 meshes with a relatively smaller pinion 15 mounted for free rotation upon a stud shaft 16 which has one 100 end supported within an opening in the frame 1 while its other end is supported within an opening in a casing 17 which is secured to the frame 1 by means of cap screws 18, thereby providing a housing for the 105 gears.

The pinion 15 is provided with an offset portion 17' to which is keyed, as at 18', a pinion 19. This pinion 19 is relatively larger than the pinion 15 and meshes with 110 a relatively smaller pinion 20 rigidly secured to a shaft 21 which extends through a cen-

tral opening in the wheel 10 and has one end journaled in the casing 17, suitable bearings in the nature of babbitt, brass or the like being provided between the wheel 10 and the 5 shaft 21 whereby free rotation of the shaft relatively to the wheel is permitted.

• A pinion 15' is mounted upon a stud shaft 16' which is carried in a manner similar to the shaft 16 at a point upon the frame 10 diametrically opposite to the shaft 16. Also 15 a pinion 19' is keyed to the pinion 15' similarly to the pinion 19 and this pinion is adapted to mesh with the pinion 20 upon the shaft 21, the second set of gearings being 20 a duplicate of that first described, and serving to increase the durability and strength of the device.

The offset portion of the wheel 10 projecting through the frame 2 has mounted thereon for free rotation a wheel 22 which is preferably of slightly smaller diameter than the frame member 2. This wheel is enlarged adjacent its circumferential edge and is provided with a series of openings to receive 25 friction blocks 23, the same being adapted for engagement with friction faces 24 upon the outer face of the frame 2. Ratchet teeth 25 are also formed upon this wheel which are adapted to be engaged by pawls 26 pivoted to the frame 2 and held in engagement with the teeth by means of springs 27 which may be mounted in enlargements 28 carried by the frame. The shaft 21 extends past the outer face of the offset portion of the wheel 30 10 and is reduced as at 29 so that a shoulder 30 is provided. Keyed for longitudinal sliding movement upon the reduced portion of the shaft is a sleeve 30' which has its periphery, adjacent its outer end, threaded to 35 receive an interiorly threaded cam member 31. This cam member 31 is provided with a plurality of inclined faces 32 upon its inner face which are adapted to be engaged by similar faces 33 upon an operating wheel 34. This wheel is mounted for free rotation upon the sleeve 30', is of any desired 40 diameter, and is provided upon its inner face with friction faces 35 arranged in alignment with the blocks 23. The peripheral edge of this operating wheel is provided, 45 with depressions similar to the depressions in the wheel 10 to receive the links of an operating element in the nature of a chain 36.

50 The free end of the lift chain 12 is adapted to be secured to a bracket 37 secured in any suitable manner between the frame members 1 and 2, and this chain is adapted to extend downwardly from the bracket, 55 thence upwardly and over the wheel 10 and then downwardly to be provided with a hook of any desired type to be engaged with the object or material to be hoisted, while the operating chain 36 is adapted to extend over 60 the wheel 34 whereby pulling upon the same

will rotate the wheel, the said chain 36 being endless if so desired.

In order to retain the chain 36 in engagement with the wheel 34 I secure to any suitable portion of the frame, a plurality of retaining elements 38 which are adapted to overlie the chain to prevent its accidental removal from the wheel.

In order to prevent the lift portion of the chain 12 from becoming engaged with the slack thereof occurring when the device is operated, I secure between the frame members 1 and 2 below the wheel 10, a bracket 39 which is provided with an upwardly extending arm 40 disposed adjacent the recesses of the wheel. As the loose portion of the chain engages this arm it is caused to be disengaged from the recesses of the wheel and directed away from the same so that the lift is in no way interfered with by the slack, the bracket 39 serving to at 80 all times hold the slack portion of the chain in spaced relation from that portion under tension.

In operation, assuming the wheel 34 to be 90 free to revolve, the hook upon the end of the chain 12 is engaged with the object to be hoisted and a pull exerted upon the chain 36 in the direction of the arrow shown in Fig. 1 of the drawings. The angular faces 95 of the wheel 34 and the cam member 31 are at this time in close contact so that as slight rotation is imparted to the wheel upon pulling the chain 36 the cam member will be caused to rotate upon the sleeve 30' and because of 100 its threaded engagement therewith will be unscrewed so as to move outwardly into binding engagement with the nut 40 threaded and locked upon the outer reduced end of the shaft 21. Thus the wheel together 105 with the cam member will be permitted a slight outward movement as an entirety whereas the sleeve will be forced over against the hub of wheel 22 to disengage 110 the friction block 23 from the friction face 115 of the operating wheel 34, whereby the wheel may be freely operated to rotate the shaft 21 which, through the gears 19, 15, and 13 will rotate the wheel 10 to operate the chain 12. Upon releasing the operating 120 chain to free the load for lowering reverse movement of the shaft 21 due to the weight of the object being lifted will cause the sleeve 30' to be rotated which, because of its threaded connection with the cam member 125 31, will revolve the cam member 31 without necessarily causing it to screw onto the sleeve, since the operating wheel reverses easily with it and the weight of the chain offers but slight resistance. The load may 130 thus be lowered by merely letting go of the chain. However, to prevent the load from descending entirely or to hold it in suspension, it is only necessary to grasp the chain and hold the wheel 34 from reversing, in 135

which case, the continuous rotating of shaft 29 will, by reason of the tendency it gives to cam member 31 to screw onto the sleeve, cause the latter to force the operating wheel over against the friction block 23, the latter in turn being frictionally engaged by the faces 24 of the frame member 2, limiting any further sliding movement of the operating wheel in that direction and thus causing the cam member 31 to be separated from the wheel by the action of their respective cam surfaces, this action tending to move the cam member outwardly until it abuts against the nut 40. This will result in the blocks 23 being frictionally engaged by the faces 24 and 35 upon the frame member 2 and wheel 34 respectively so that further rotation of the wheel 10 will be prevented, the pawls 26 engaging with the ratchet teeth 25 serving to prevent rotation of the wheel 22 carrying the blocks 23 in a reversed direction, as will be understood. It is not necessary or essential that the ratchet wheel 22 rotate with the wheel 34 when the device 25 is in operation, and it is probable that the motion of the ratchet wheel will be intermittent, the same being made rotatable in order to permit the friction faces to firmly engage before rotation of the wheel 10 is stopped. 30 It will be noted that the tendency of the angular faces of the wheel 34 and cam member 31 is to work away from each other, thus wear between the friction faces of the brake-members is taken up automatically.

It is to be understood that the wheel 10 may be replaced by a drum to receive a cable, but slight alterations of the device being necessary in order to so adapt the same. 40 Also it will be obvious that by replacing the wheel 34 by one having gear teeth thereon a motor or another operated gearing of any desired type may be applied to the device to supply the necessary power for operation. 45 It will also be understood that the housing formed by the casing 17 may be provided with a bath of oil to lubricate the gears arranged therein so that the device in use will be thoroughly lubricated and practically noiseless.

From the foregoing description taken in connection with the accompanying drawings, it is thought that the construction and operation of the improved hoisting device 55 will be clearly understood and while I have herein shown and described certain specific embodiments of my invention, I do not wish to be limited thereto except for such limitations as the claims may import.

60 I claim:

1. In a device of the character described, a frame, a lift wheel carried by said frame, a shaft having a reduced end journaled in said wheel for free rotation, a plurality of

gears connecting the wheel with the shaft, 65 a sleeve keyed for sliding movement upon the reduced end of the shaft, a wheel loose on said sleeve, a member threaded for rotation on said sleeve, and angular engaging cam faces between the member and the said 70 operating wheel.

2. In a device of the character described, a frame, a wheel mounted on said frame, a shaft, gears connecting said wheel with said shaft whereby the latter is rotated, a 75 sleeve slideable upon said shaft, a cam member threaded for movement upon said sleeve and an operating wheel for turning said cam member on said sleeve whereby the latter may, at times be moved outwardly 80 from said operating wheel, means on said shaft to limit sliding movement of the sleeve, means to limit movement of the cam member and frictional means interposed between the frame and the last mentioned wheel, said 85 frictional means adapted to be held spaced from said operating wheel by the forward sliding movement of the said sleeve.

3. In a device of the character described, a frame, a wheel journaled thereto with its 90 hub extended, a shaft, gears connecting the wheel with the shaft, a brake wheel mounted upon the extended hub of the said first wheel and on the outside of the frame, friction blocks carried by said brake wheel, 95 ratchet teeth formed below the friction blocks, pawls carried by the frame for engagement with said teeth, operating means and a sleeve slidably supporting said operating means upon said shaft, said sleeve being keyed to said shaft and adapted for sliding abutment with said brake wheel for moving it into frictional engagement with the side of the said frame for preventing rotation of said shaft. 105

4. In a device of the character described, a frame, a lift wheel carried thereby, a shaft, gears connecting the wheel with the shaft, said shaft being reduced to provide a shoulder, a sleeve keyed to slide on the 110 reduced portion of the shaft, a cam member threaded upon said sleeve, a nut carried by the reduced portion of the shaft, an operating wheel loosely mounted upon said sleeve, cam faces formed on the operating wheel for engagement with the cam faces upon the cam member, a brake wheel mounted to revolve freely between the said frame and the inner end of the sleeve, 115 ratchet teeth formed on said brake wheel, 120 and pawls carried by the frame for engagement with the teeth.

In testimony whereof I affix my signature in presence of two witnesses.

WILLIAM H. DARRAH.
